CEILING RUNNERS AND PARTITION STRUCTURE

Nels Nelsson, Chicago, Ill., assignor to United States Gypsum Company, Chicago, Ill., a corporation of Illinois

Application November 16, 1949, Serial No. 127,566

3 Claims. (Cl. 72—46)

This invention relates to a partition wall construction and more particularly to improvements in a ceiling runner, and the present application being a continuation-in-part of my pending patent application Serial No. 769,334, filed August 19, 1947, now abandoned.

It is one of the objects of the present invention to provide a ceiling runner to be used in combination with wall members and associated holding clips for erecting a partition wall having improved structural characteristics.

It is a further object of the present invention to provide a ceiling runner to be used in combination with wall members and associated holding clips for erecting a partition wall wherein the keying effect of the plaster subsequently applied to the wall member is improved.

A further object is to provide a ceiling runner which is simple yet durable in construction, effective in operation, and inexpensive to produce.

Further and additional objects will appear from the description, accompanying drawings and appended claims.

In accordance with one embodiment of this invention, a ceiling runner is provided which is substantially L-shaped in cross section. The shorter flange or leg section of the runner is fastened to the ceiling while the longer flange or leg section extends downwardly therefrom. The longer leg section has formed therein a plurality of elongated openings arranged in staggered, overlapping relation. The lower edge of the longer flange is offset so as to engage the adjacent surface of the wall members and hold them in spaced relation with respect to the remainder of said flange when the wall members are positioned adjacent thereto.

For a more complete understanding of this invention reference should now be made to the drawings, wherein:

Fig. 1 is a fragmentary front elevational view of an un plastered partition wall;

Fig. 2 is a sectional view of the partition wall taken along line 2—2 of Fig. 1;

Fig. 3 is a fragmentary perspective view of the ceiling runner;

Fig. 4 is an end view of the ceiling runner;

Fig. 5 is a partial vertical sectional view of a partition erected in accordance with the present invention;

Fig. 6 is a fragmentary horizontal sectional view of a partition wall employing a facing strip;

Fig. 7 is a fragmentary perspective view of the facing strip shown in Fig. 6, and

Fig. 8 is a fragmentary side elevational view of the facing strip shown in Fig. 6 shaped to conform to an arch.

Referring now to the drawings and more particularly to Figs. 1 and 2, a partition wall construction is shown comprising an elongated ceiling runner 10 fastened to an overhead supporting member 11 by means of nails or other fasteners 12, a plurality of plasterboards 13a and 13b arranged in an upright side-by-side position, and a plurality of holding clips 14 adapted to cooperate with ceiling runner 10 for resiliently holding plasterboards 13a and 13b thereagainst. The clip 14 is made of heavy wire, the shorter leg 19 being bent slightly inwardly, so as to grip the downwardly extending leg of the ceiling runner.

2

The ceiling runner 10 is substantially L-shaped in cross section and has its shorter flange or leg section 15 secured in place by the nails 12. The flange 15 is slightly bowed or longitudinally bent along the line 15', as shown in Figs. 3 and 4, and is provided with a plurality of longitudinally spaced openings 16 through which the nails 12 extend. When the runner is fastened to member 11, the flange 15 is flexed or deformed into a substantially flat condition as shown in Fig. 2. The tension thus created causes flange 15 to press snugly against the surface to which it is applied and against the heads of nails 12, thereby holding the runner firmly in place. A further advantage afforded by the bowing of flange 15 is that the flange is more rigid and less likely to be bent or kinked while being handled.

The longer flange or leg section 17 extends downwardly from the member 11 and is disposed at a substantially right angle with respect to flange 15. Flange 17 is provided with a plurality of elongated openings 18 arranged in vertically spaced rows and in overlapping, staggered relation with respect to one another. The openings 18 enable the short, runner-engaging leg 19 of clip 14 to extend therethrough as shown in Fig. 2. The lower or free edge portion 20 of flange 17 is offset a slight amount so that only the extreme edge 20' engages the adjacent surface of the plasterboards 13a and 13b when they are operatively positioned against runner 10. One of the advantages of offsetting lower edge 20 is to give greater rigidity to the flange itself. A further advantage is that a firmer grip by the holding clip 14 on the plasterboards is obtained. Also, the space 21 provided between the remainder of flange 17 and the adjacent surface of the plasterboard affords a better keying for the plaster which is subsequently applied to the plasterboards.

The method of erecting the partition wall is as follows: The ceiling runner is secured to a ceiling or ceiling support, and a floor runner 22 is secured to the base support 23 in proper alignment with respect to the ceiling runner by fasteners 25, such as nails. The lower edges of the plasterboards are then positioned or seated in the floor runner, which in this instance is shown to be in the form of a channel that is U-shaped in cross section, and the plasterboards are then placed in an upright position so that the upper edge portions thereof contact the edge 20' of the offset portion 20 of the depending flange 17. The holding clips 14 are then operatively positioned. In this operation each clip is arranged in a substantially horizontal position whereby the shorter leg 19 thereof may be inserted through one of the elongated openings 18 formed in the ceiling runner. The clip is then turned substantially 90 degrees to a vertical position whereby the short leg embraces the outer surface of long flange 17 of the ceiling runner and the longer leg 7 of the clip resiliently engages the outer surface of the plasterboard. The two legs of the clip 14 are inwardly inclined relative to each other, but when in position the legs are substantially parallel. This insures a resilient holding effect which keeps the clips in place until the plaster is applied to the structure.

After the plasterboards have thus been erected, the partition is completed by applying plaster 24 to both sides thereof, taking particular care to fill the space 26 between the top of the plasterboards and the overhead supporting member 11 and also to insure the passage of sufficient plaster through the openings 18 so as to form plaster keys 27 between the inside surface of the depending leg 17 of the ceiling runners 10 and the plasterboard. The formation of these keys is assured by the spacing of the leg 17 from the plasterboards by the inwardly bent flange 20 which rests with its edge 20' against the plasterboards. These keys tightly lock the plaster against the plasterboards and prevent possible separation and for-

mation of cracks along the line of the bottom edge of the leg 17. The plaster also surrounds the clips 14, thus locking them in place. The overall result is a strong, rigid partition having two smooth outer surfaces which effectively conceal the runners, plasterboards and clips. As the only tool required for erection of the structure is a hammer, even relatively unskilled workmen can readily and effectively erect a partition.

In Figs. 6 through 8 a substantially T-shaped facing strip 28 is shown which embodies the ceiling runner 10 hereinbefore described. The shorter flange or leg section 15 of the runner 10 is secured by spot welding or any other suitable means to the inside surface 30 of a substantially flat elongated member 31. The edges 32 of the member are turned downwardly a slight amount so as to more effectively hold in place the plaster 33, which is applied to both sides of the plasterboard 34, as shown in Fig. 6. Furthermore the bent edges 32 protect the exposed outside corners of the partition 35.

To effect curvature of the facing strip 28 to conform to a rounded inside corner, such as in an archway construction, the longer flange 17 of runner 10 is transversely cut or slit as shown in Fig. 8.

The improved keying effect of the plaster in a partition employing runner 10, as hereinbefore mentioned, is likewise incorporated in partition 35 using facing strip 28. Holding clip 14 or any other suitable means may be used to hold the facing strip 28 resiliently against the plasterboard 34. In some instances it may be desirable to secure the plasterboard to the flange 17 of the facing strip by means of a tie wire extending transversely through the plasterboard and the openings 18 of the flange (not shown), so as to prevent relative sliding movement of the plaster board and facing strip. The facing strip 28 is so arranged with respect to the board 34, that a space is provided between member 31 and the edge of the board 34; which space is subsequently filled with plaster 33, as shown in Fig. 6.

Thus it will be seen that a partition wall construction has been provided which may be readily erected or dismantled and also has many improved structural characteristics. Furthermore, the ceiling runner employed in this construction is durable and rigid and adapted to withstand rough treatment while being handled and is simple in design, effective in operation, and inexpensive to produce. A facing strip incorporating the ceiling runner has been provided which likewise has many improved structural advantages.

While I have disclosed the preferred embodiment of this invention, it will be understood, of course, that the invention is not to be limited thereto since many modifications may be made, and it is contemplated, therefore, by the appended claims, to cover any such modifications as fall within the true spirit and scope of this invention.

I claim:

1. In a wall, the combination of a supported lath panel, a runner for reinforcing an exposed edge of the wall, and a clip securing said runner to said supported lath panel, said runner comprising a substantially flat head section having a width corresponding substantially to the thickness of the wall and a length corresponding substantially to the length of the exposed edge of the wall, said head section being disposed in spaced relation with respect to the edge of said lath panel, and an elongated apertured flange section of substantially the same length as said head section disposed intermediate the elongated edges of said head section and extending angularly from said head section, said flange section having an angularly offset portion spaced from said head section and protruding from one side of said flange section toward the adjacent surface of said lath panel whereby only said offset portion is in contact with the adjacent panel surface and the remainder of said flange section is spaced therefrom; said clip comprising a substantially U-shaped body em-

bracing the edge of said lath panel and having one leg thereof projecting through one of the apertures of said runner flange section and resting against said flange section, and the other leg thereof resting against the surface of said lath panel opposite said adjacent surface to effect yieldable gripping of said lath panel edge portion and said runner flange section between the legs of said clip.

2. In a wall, the combination of a lath panel, a clip, and a runner disposed adjacent one surface of said lath panel for use in securing the latter to a stationary support; said runner comprising an elongated resilient first section for attachment to such a support and deformable with respect thereto when in such attached relation, and an apertured flange second section extending angularly in one direction from said first section and being provided with an offset portion spaced from said first section and protruding from one side of said second section toward the adjacent surface of said panel whereby only said offset portion is in contact with the adjacent panel surface and the remainder of said second section is spaced therefrom; said clip comprising a hook-shaped portion with one segment thereof extending through one aperture in said second section, a second segment thereof extending from said first segment and contacting the opposite side of said flange second section from which said offset portion protrudes, and a third segment thereof extending from said first segment and contacting the surface of said panel opposite from that engaged by said offset portion whereby said clip cooperates with said flange second section to effect yieldable positive engagement of said offset portion with the adjacent surface of said panel.

3. In a plastered wall, the combination of a stationary support, a lath panel having planar exposed surfaces, a plaster coat applied to the exposed surfaces of said lath panel, a runner mounted on said stationary support and having a depending section disposed adjacent one exposed surface of said panel, and means engaging the other exposed panel surface and said depending runner section and securing said panel and runner in assembled relation; said runner comprising an elongated first flange section attached to said stationary support, and a depending elongated apertured second flange section extending angularly from said first flange section and forming said depending section disposed adjacent said one exposed panel surface, said second flange section having the elongated free edge thereof offset and protruding from one side of said second flange section toward said one exposed surface of said panel whereby only said offset edge is in contact with said exposed panel surface and the remainder of said second flange section is spaced therefrom and substantially parallel therewith and cooperates therewith to form a cavity, said second flange section being provided with a plurality of apertures disposed opposite said exposed panel surface and communicating with said cavity, a portion of said plaster coat extending through said apertures into said cavity.
